UNITED STATES PATENT OFFICE.

OSCAR ADOLPHUS BERMAN, OF CINCINNATI, OHIO.

MANUFACTURE OF CONDENSERS.

Application filed October 2, 1922. Serial No. 591,289.

To all whom it may concern:

Be it known that I, OSCAR A. BERMAN, a citizen of the United States, residing at 224 East 8th Street, Cincinnati, State of Ohio, have invented certain new and useful Improvements in the Manufacture of Condensers, of which the following is a specification.

This invention relates to improvements in the manufacture of condensers, and particularly to condensers which can be used in radio apparatus.

It is an object of the invention to provide a condenser whose capacity can be varied in an extremely simple way through the variation of the distance between parts of the condenser or of the pressure with which parts of the condenser act on each other.

It is also an object of the invention to provide a condenser in which movement is imparted to one or more of the elements of the condenser in a direction towards or away from other parts thereof in order to vary their distance or the pressure with which these parts are in engagement with each other so as to alter the capacity of the condenser.

The invention also has the object of providing a simple mechanism through which one of the conductive plates may be moved positively towards or away from the adjacent dielectric member without, however, interrupting the conduction of current to or from the electric element in question.

With these and other objects in view, an embodiment of the invention is illustrated in the accompanying drawing by way of example and is described in the following specification.

In the drawing:

Fig. 1 is a front elevation of a panel showing a portion of the condenser;

Fig. 2 is a side elevation or edge view of a condenser composed of two electric surface elements and one dielectric member, and

Fig. 3 is a sectional view through the condenser showing the mechanism for moving one of the parts relatively to the others.

Fig. 4 is a rear view of the condenser mounted on a panel.

While it is known in the art of varying the capacity of condensers to space electric surface elements of the condenser from each other, using air as a dielectric and to insert portions of variable area of conductive

surface elements into the space between the first named conductive parts, the present invention is directed to an improvement whereby the area of the cooperating surface elements is not altered while the distance between cooperating electric elements or cooperating elements and dielectric elements is varied.

For the purpose of illustrating the apparatus the condenser is shown to be mounted on a support 1, which may consist of a suitable insulating member, as, for instance, wood or a composition as it is frequently used in instruments of this character, and which may, for instance, be the closure or top member of a box in which other parts of an instrument (not shown) are arranged. One of the conductive surface elements of the condenser, shown here in the form of a disc 2, having an opening 3, is secured in a suitable way to one surface of the support, as, for instance, by cementing a disc of tin foil to said support. The disc 2 surrounds a perforation 4, which extends through the entire thickness of the support. The plate 3, which in the present case is shown to be made of tin foil, is covered by a dielectric member 5 made of mica or some other insulating composition, and this dielectric element 5 also is shown in the form of a disc having a central opening 6 in registration with the central opening 3 of the first mentioned electric surface elements and in axial alignment with the opening 4. A second electric surface element 7, made of relatively strong conductive material, as, for instance, a sheet of phosphor bronze or the like, also is concentrically arranged with respect to the other parts of the condenser. This companion electric member 7 has a small central opening through which extends the spindle or screw 8 projecting from the rear of the companion electric member and secured thereto, for instance, by means of a nut which may be fixedly connected by solder or the like with the projecting end of the spindle 8 and also with the rear surface of the disc 7.

That end of the screw spindle 8 which is connected with the nut 9 is in permanent contact with the free end of a conductor 10, as, for instance, a spring made of phosphor bronze or some other suitable conductive material, the other end of this spring of phosphor bronze being united with the panel or support 1, and the point of attach-

ment serving at the same time as a fastening means for a binding post 11.

The screw spindle 8 projects through the registering openings 3, 4 of the two other surface elements 2, 5 of the condenser without contacting the same and the support 1 is provided with a nut 12 which is rigidly secured in place within the support 1. Any desired means may be used to hold the nut 12 against rotary or axial displacement, as, for instance, a pin 13 and a flange 14. The screw spindle 8 furthermore is provided on the side of the support 1 opposite to that on which the condenser is located with a knob 15 rigidly connected therewith, whereby upon rotation of the knob a rotary movement is imparted to the screw; and as this screw extends through the nut 12 in the support of the condenser, an axial movement is transmitted to the electric plate 7 thereby altering the distance of the electric elements 2 and 7, or of the dielectric member 5 and the plate 7 from each other. It is obvious, therefore, that upon manipulation of the screw spindle also the pressure with

which one of the electric members is forced towards the other electric or dielectric member is altered, and that in accordance with this pressure also the capacity of the entire condenser may be varied.

30

I claim:

In an electrical condenser an insulating support, a metal disc secured thereto so as to be engaged over its whole area with the support, an insulating disc, a nut fixed in said support, a screw in engagement with said nut, extending through the support, the metal disc and the insulating disc without contacting therewith and having a handle rigidly connected thereto at its upper end, a second metal disc rigidly fastened to said screw adjacent its lower end, a binding post on said support and a spring secured to the binding post and yieldingly pressing against the lower end of the screw acting at the same time as electrical connection and securing the screw against accidental rotation.

In witness whereof I affix my signature.
OSCAR ADOLPHUS BERMAN.
